UNITED STATES PATENT OFFICE.

AUGUSTUS F. KLASING, OF CHICAGO, ILLINOIS, ASSIGNOR TO THE KLASING CAR BRAKE COMPANY, A CORPORATION OF COLORADO.

APPARATUS FOR MANIPULATING RAILWAY-CAR BRAKES.

1,420,554.

Specification of Letters Patent. Patented June 20, 1922.

Application filed July 9, 1920. Serial No. 395,061.

To all whom it may concern:

Be it known that I, AUGUSTUS F. KLASING, a citizen of the United States, residing at Chicago, in the county of Cook and State of Illinois, have invented certain new and useful Improvements in Apparatus for Manipulating Railway-Car Brakes, of which the following is a specification.

My invention relates to railway car brake mechanisms, and more particularly to a hand operated apparatus for applying and releasing the brakes of a railway car, for example, a freight car, in switching or on other occasions when the brakes are controlled manually. A freight car is usually provided with a hand operated braking mechanism consisting of a brake staff on the lower end of which is wound a chain connected with a brake rigging on the under side of the car, the upper end of the staff being provided with a hand wheel and the brakes being held in set position by means of a dog and ratchet device which the brakeman operates with his foot when the brakes are released. This common type of apparatus is uncertain in its functioning, slow of operation and requires very considerable effort in setting the brakes, the brakeman frequently using a club on the wheel to obtain increased leverage, besides necessitating great care when the brakes are released since the reaction of the hand wheel is very quick and violent. As a consequence accidents in switching and in making up trains, especially in hump yards, are not infrequent, resulting often in the loss of life or limb to the trainmen, injury to the cars through impact, and damage to cargoes.

One of the principal objects of my invention is to provide a new and improved apparatus for manipulation of railway car brakes whereby the brakes may be set and released without danger to the trainmen and whereby the slack in the brakes may be quickly taken up and great power applied by the shoes at the time they are brought into contact with the wheels.

A further object is to provide an apparatus which will be simple, strong and compact in structure with the working parts so arranged as not to project unduly from the body of the car or interfere with other mechanisms thereon.

A further object is to provide a detent device in connection with the apparatus for

maintaining the brake shoes in contact with the wheels, which detent device may be manually set for the release of the brakes and is automatically reset to its operative position when the release has taken place.

A further object is to provide certain arrangements for housing the movable parts of the apparatus so as to prevent the same from being injured or from being clogged by dust, cinders, ice, snow, and the like.

Another important object of the invention is to provide a manually operated brake mechanism which will be positive and certain in its functioning and which will consist of parts so constructed and assembled that there is little or no danger of the apparatus being disabled under any ordinary service conditions.

A further object of the invention is to improve upon the brake operating mechanisms shown and described in my applications Serial No. 220,467 filed March 5, 1918, and Serial No. 260,018 filed October 28, 1918. The present application is a continuation in part of my co-pending application Serial No. 302,565 filed June 7, 1919.

The invention is illustrated, in a preferred embodiment, in the accompanying drawings wherein—

Fig. 1 is a fragmentary side elevation of the end of a railway box car having installed thereon a brake manipulating apparatus constructed in accordance with my invention.

Fig. 1^a is a plan view of a modified arrangement showing the power applying device set at an angle to the car end.

Fig. 2 is a fragmentary view, in perspective, of the power applying device operated by the brakeman.

Figs. 3 and 4 are vertical sectional views on lines 3—3 and 4—4, respectively, of Fig. 1.

Fig. 5 is a detail view, in perspective, of the upper end of the movable rack bar forming part of this apparatus.

Fig. 6 is a similar view of the lower portion of the rack bar.

Fig. 7 is a sectional plan on line 7—7 of Fig. 3.

Fig. 8 is a sectional plan on line 8—8 of Fig. 4.

Fig. 9 is a fragmentary sectional view on line 9—9 of Fig. 1.

of the parts of the detent employed for holding the rack bar in the position which it assumes when the brakes are set.

Fig. 12 is a sectional view of the rocking transmission element and associated parts, employed for transmitting movement from the power applying device to the brake operating connection on the under side of the car.

10 Fig. 13 is a front elevation of the parts shown in Fig. 12, and

Fig. 14 is a sectional view, looking in the direction of the arrows, on line 14—14 of Fig. 12.

15 The brake apparatus of my invention may be applied to various types of railway cars. The preferred form of the invention herein disclosed is illustrated as installed upon a box car. In Fig. 1 25 designates the body 20 of the car, a portion of the end wall being shown at 26 in Fig. 2. The brake apparatus consists essentially of a power applying device, which, in the illustrated embodiment of the invention is shown fastened to 25 the end wall of the car near the top thereof, this device being operated by means of a hand lever; a horizontally disposed brake operating connection extending under the car body and secured in any desired manner 30 (not shown) to the brake beams; a transmission element arranged under the car at the end thereof, to which the brake operating connection is fastened, and a vertically, or substantially vertically, extending connection 35 between the transmission element and the power applying device. The brake operating connection is shown as consisting of a rod 27 and a short piece of chain 28 connecting the rod to the transmission element 29. A longer chain might take the place of the chain and rod or the chain might be omitted and the rod connected directly to the transmission element. 30 indicates a rod (here also a chain might be used 40 but a rod is preferable) connecting the transmission element 29 with a vertically movable member 31 forming part of the power applying device. This latter is constructed as follows: 32 is a housing formed 45 with lugs 33 by means of which it is fastened to the end wall of the car. The lower part 34 of the housing is larger in cross section than the upper part and is formed on one of its inner walls 35 with teeth constituting 50 a rack 36. The vertically movable member 31 consists of a rack bar having teeth 37 on its inner side. The rack bar is arranged to move vertically in the housing. 38 is a pinion adapted to travel upon the fixed rack 55 36 and to engage the teeth of the movable rack bar 31, the pinion being formed with gudgeons 39, 40 which are guided in slots 41, 42 formed in the sides of the housing. Fixed 60 to a squared projection 43 on the gudgeon 40 is a ratchet 44 adapted to be engaged by

a pawl 45 which is pivoted on a stud 46 within the forked end 47 of the brake operating lever 48. The extremities 49, 50 of the forked portion 47 of lever 48 are formed with openings and mounted to turn upon the 70 gudgeon 42 and a stud 51, respectively, the stud being formed integrally with gudgeon 40 and its square projection 43. The ratchet, pawl and upper end of the operating lever are partially enclosed by a hood 75 52, which is open in front and at the bottom and is preferably made integral with housing 32, 34. The pawl 45 has a weighted tail piece 53 which tends to keep the pawl in engagement with ratchet 44. The ratchet 80 is rotated by raising operating lever 48, pinion 38 rotating with the ratchet and traveling up rack 35. A platform 54 (Fig. 1) is preferably provided on the end of the car for the brakeman to stand upon when 85 setting or releasing the brakes. The rack bar 31 is given an upward travel which is double the upward travel of the pinion 38. This gives a rapid take up of the slack in the brake operating mechanism, the rapidity 90 with which the slack is taken up being increased by the construction of the transmission element as will hereafter appear. The front side of the rack bar 31 is formed with a lug 55 having an opening 56 therein. The 95 upper end of the connecting rod 30 extends through this opening, the rod being formed with a head 57 to engage the lug. The back wall 58 of the hood within which ratchet 44 travels, is so arranged that on the return or 100 down stroke of the operating lever 48 the extremity of the tail 53 of pawl 47 is brought to bear against it, the pawl being thereby forced from its engagement with ratchet 44. A recess 59 is provided at the 105 lower edge of the hood which permits the pawl to remain in engagement with the ratchet when the lever is hanging in a vertical position and the pinion and ratchet are in their lowermost positions.

110 The following means are employed for holding the rack bar in its raised position. The housing 32, 34 is formed with a hood-like enlargement 60, the lower edge 61 of which is formed with a groove 62 to provide a bearing for the rounded lower edge 63 of a rocking dog 64 (Fig. 10) formed with teeth 65 adapted to engage two series of spaced teeth 66 (Fig. 5) on the rear side of rack bar 31. The dog has a laterally projecting stud 67 which extends out through an opening 68 in the side of the hood 60 (Fig. 8) so as to be engaged by a rocking member 69 (Fig. 11) provided with a thickened portion 70 to give it 115 weight, the rocking member being formed with perforated ears 71, 72 by means of which it is pivoted between spaced webs 73, 74 formed on the housing 32, 34. The rocking member or pivoted weight is formed 120 125 130

with a handle 75 and is adapted to bear against either side of the stud 67 to force the dog 64 against the teeth on the rack bar or to rock the dog so as to disengage it from the rack bar. Fig. 9 shows in the full lines the first mentioned position of the weight. The dotted lines indicate the other position in which it tends to disengage the dog from the teeth of the rack bar.

10 The detent device above described is preferably so constructed that the weight is automatically re-set to its position holding the dog in engagement with the rack bar when the rack bar drops to release the brakes. With this in view the dog is formed with a lug 76 which extends into the slot between the two series of teeth 66 on the back side of the rack bar 31. This slot does not extend to the upper end of the 15 rack bar, the bar being provided at its upper end in line with the slot with a lug 78 which, it will be seen, is adapted to strike against the lug 76 on the dog when the rack bar falls to its lowermost position. This 20 tilts the dog into engagement with the teeth 66 of the rack bar and the rack bar and connecting rod 30 are heavy enough to cause the impact of lug 78 against lug 76 to throw the weighted element 69 into the 25 position in which it tends to force the dog against the rack bar. The lug 78 has a cam face or beveled off corner 79 adapted to bear against the dog 64.

The transmission element 29, whereby the 30 upward pull on rod 30 is changed to a horizontal outward pull on the brake operating connection 27, 28, consists of a lever having a rolling fulcrum. That is, the device has translatory movement as well as angular movement. The translatory movement 35 is preferably in a diagonally downward direction, having reference to the setting of the brakes, so that the transmission element moves bodily away from the brakes and at the same time away from the power 40 applying mechanism. The rolling fulcrum consists preferably of a sector gear 80 formed integrally with the lever, adapted to engage a diagonally disposed rack 81 formed 45 along the upper inner surface of a channel-shaped casting 82 secured by lag screws 83 to the under side of the car body and preferably provided with a flange 84 fastened by screws 85 to the end wall of the car. The 50 sector gear is preferably formed with guide 55 geons 86 which move through guide channels 87 formed in the side walls of the channel-shaped casting 82. The upper end of the lever 29 is formed with a slot 88 to receive the chain 28; when the lever is 60 rocked, the chain being secured to the lever by pin 89 at the bottom of slot 88.

By the arrangement just described, the take-up resulting from the angular movement of lever 29 is increased through the

movement of the lever down rack 80. As a result it is practical to use this species of transmission device since the arms of the lever need not be as long as they would have to be, to insure maximum take-up if 70 an ordinary bell crank with a fixed fulcrum point were employed. This is important because in many cars at least there would not be space in vertical direction for 75 rocking movements of sufficient amplitude to insure a maximum take-up by means of a device having a fixed pivot. Moreover, it would be in many cases objectionable to have on the bottom of a car a bell crank lever, the arms of which were of sufficient 80 length for taking up slack.

Summary of operation.—The brakeman standing on platform 54 raises lever 48, rotating and raising ratchet 44 and pinion 38. The pinion climbing on fixed rack 35 im- 85 parts a movement of double amplitude to the rack bar 31 and connecting rod 30. At the end of the stroke the lever is allowed to drop and is disengaged from the ratchet by its tail piece coming against the surface 58 90 of the housing. The brakes may be set in one stroke of the lever or it may require more than one stroke, according to the amount of slack in the brake connections. The rocking and rolling transmission element 29 im- 95 parts movement to the brake operating connection 27, 28, which is of very considerable amplitude in comparison with the relatively small size of transmission element. The bodily downward movement of the lever on the rack 100 away from the brakes and away from the power applying device increases the take-up on the brakes giving a length of movement which could only be obtained, if the fulcrum of the lever were fixed, by employing 105 a lever with much longer arms. The dog 64 by engaging teeth 66 on the back of the rack bar 31 holds the rack bar in its elevated position. When the brakeman wishes to release the brakes the pivoted weight 69, 70 is 110 reversed so that it bears on the inner side of stud 67 instead of upon the outer side thereof. The weight does not immediately release the dog from the rack bar but operates to do so as soon as the rack bar is raised a 115 trifle, which can be done by lifting a little on lever 48, to free the dog from the pressure of the rack bar. The bar will then drop as the lever is dropped, releasing the brakes instantaneously. When this occurs there is no re- 120 action on the lever which is entirely disengaged from ratchet 44 so that one serious cause of danger, inherent in the common type of hand brake mechanism, is eliminated.

When the rack bar falls to its lowermost position lug 78 strikes against the lug 76 on the dog, throwing the dog back into mesh with teeth 66 and tilting the weight 64 to its operative position in which it holds the dog in engagement with the rack bar. When the 125

rack bar is raised the cam surface 79 on its upper extremity is brought to bear against the dog 64 so as to aid in forcing the dog out of engagement with the teeth of the rack bar.

In Fig. 1^a is illustrated a slightly modified arrangement, in which the housing 32' is secured at an angle to the end wall 26' of the car, so that the brakeman in setting the 10 brakes, may stand on the platform 54' between the operating lever 48' and the car end. This arrangement provides greater security for the brakeman. In other respects the apparatus is the same as that previously 15 described.

I claim:

1. The combination with a railway car and its brakes, of a brake operating connection under the car, a vertically movable member 20 on the end of the car, a transmission element mounted so that it is rocked and its fulcrum given translatory movement, and means comprising a lever adapted to be oscillated to impart step by step upward movement to the 25 vertically movable member.

2. The combination with a railway car and its brakes, of a brake operating connection under the car, a vertically movable member on the end of the car, a transmission 30 element mounted so that it is rocked and its fulcrum given translatory movement, and means for raising said vertically movable member comprising a rolling member engaging the vertically movable member, and 35 a lever oscillatable to revolve and raise said rolling member step by step.

3. The combination with a railway car and its brakes, of a brake operating connection under the car, a vertically movable member 40 on the end of the car, a transmission element mounted so that it is rocked and its fulcrum given translatory movement, means for raising said vertically movable member comprising a rolling member engaging the vertically 45 movable member, a lever oscillatable to revolve and raise said rolling member step by step, and a detent to hold the vertically movable member in raised position which can be manually set in the raised position of the 50 vertically movable member to permit the release of said vertically movable member therefrom.

4. The combination with a railway car and its brakes, of a brake operating connection 55 under the car, a vertically movable member on the end of the car, a transmission element mounted so that it is rocked and its fulcrum given translatory movement, means for raising said vertically movable member 60 comprising a rolling member engaging the vertically movable member, a lever oscillatable to revolve and raise said rolling member step by step, a detent to hold the vertically movable member in raised position which 65 can be manually set in the raised position of

the vertically movable member to permit the release of said vertically movable member therefrom, and means whereby on the downward movement of the vertically movable member the detent is automatically reset to 70 its operative position.

5. In combination with a railway car and its brakes, apparatus for manipulating the brakes comprising a brake operating connection under the car, a rolling transmission 75 element, a rack fixed on the end of the car, a vertically movable rack connected with the transmission element, a pinion interposed between said racks, and an operating lever and a ratchet and pawl mechanism 80 associated with the pinion for causing it to roll up the fixed rack.

6. In combination with a railway car and its brakes, apparatus for manipulating the brakes comprising a brake operating connection under the car, a rolling transmission element, a rack fixed on the end of the car, a vertically movable rack connected with the transmission element, a pinion interposed between said racks, an operating 85 lever and a ratchet and pawl mechanism associated with the pinion for causing it to roll up the fixed rack, and a detent for holding the rack in raised position which can be set to effect the release of the rack. 90

7. In combination with a railway car and its brakes, apparatus for manipulating the brakes comprising a brake operating connection under the car, a rolling transmission element, a rack fixed on the end of the car, a vertically movable rack connected with the transmission element, a pinion interposed between said racks, an operating lever and a ratchet and pawl mechanism associated with the pinion for causing it to roll up 100 the fixed rack, and a detent for holding the rack in raised position which can be set to effect the release of the rack, and automatically reset to operative position when the rack moves downwardly. 110

8. In combination with a railway car and its brakes, apparatus for manipulating the brakes comprising a fixed rack, a movable rack, a pinion adapted to roll on said fixed rack and raise the movable rack, a ratchet 115 on the pinion, a lever pivoted on the pinion, and a pawl pivoted to the lever to engage the ratchet.

9. In combination with a railway car and its brakes, apparatus for manipulating the 120 brakes comprising a fixed rack, a movable rack, a pinion adapted to roll on said fixed rack and raise the movable rack, a ratchet on the pinion, a lever pivoted on the pinion, a pawl pivoted to the lever to engage 125 the ratchet, and a housing enclosing the pinion, ratchet and pawl having a surface against which the pawl is brought to bear on the back stroke of the lever to throw the pawl out of engagement with the ratchet. 130

10. In combination with a railway car and its brakes, apparatus for manipulating the brakes comprising a fixed rack, a movable rack, a pinion adapted to roll on said fixed rack and raise the movable rack, a ratchet on the pinion, a lever pivoted on the pinion, a pawl pivoted to the lever to engage the ratchet, and a detent to hold the movable rack in fixed position.
11. In combination with a railway car and its brakes, apparatus for manipulating the brakes comprising a fixed rack, a movable rack, a pinion adapted to roll on said fixed rack and raise the movable rack, a ratchet on the pinion, a lever pivoted on the pinion, a pawl pivoted to the lever to engage the ratchet, a detent to hold the movable rack in fixed position comprising a dog to engage the movable rack, and a weight to hold the dog in engagement with the rack which may be set to force the dog out of engagement with the rack.
12. In combination with a railway car and its brakes, apparatus for manipulating the brakes comprising a fixed rack, a movable rack, a pinion adapted to roll on said fixed rack and raise the movable rack, a ratchet on the pinion, a lever pivoted on the pinion, a pawl pivoted to the lever to engage the ratchet, a detent to hold the movable rack in fixed position comprising a dog to engage the movable rack, a weight to hold the dog in engagement with the rack which may be set to force the dog out of engagement with the rack, and means operated by the downward movement of the rack for resetting the weight to its operative position.
13. In combination with a railway car and its brakes, apparatus for manipulating the brakes comprising a vertically movable member formed with a series of teeth, means connecting the same with the brakes, a fixed support, a dog having a rocking bearing on said support and adapted to engage said teeth, and a weight pivoted to the support and adapted in one position to bear against the dog to hold the same against the vertically movable member and in another position to bear against the dog so as to tend to force it from engagement with the vertically movable member, said vertically movable member and dog formed with coengaging parts which operate at the end of the downward movement of the vertically movable member to throw the weight from its inoperative to its operative position.
14. In combination with a railway car and its brakes, apparatus for manipulating the brakes comprising a housing, a vertically movable member in said housing formed with a series of teeth, a dog in said housing having a rocking bearing thereon and formed with a tooth to engage the teeth of the vertically movable member, the housing having an opening in the side and the dog having a stud projecting therethrough, and a weight pivoted on the outside of the housing adapted to be moved to bear against one side or the other of said stud to force the dog into or out of engagement with the vertically movable member.
15. In combination with a railway car and its brakes, apparatus for manipulating the brakes comprising a housing on the car having a rack formed on the inside thereof, a rack bar movable in the housing, a pinion between the rack bar and rack, a hood on the housing open at one side, a ratchet in the hood rigid with the pinion, a lever pivoted with respect to the ratchet, a pawl on the lever to engage the ratchet, said housing formed with an enlargement having an opening in one side, a dog having a rocking bearing on said enlargement and formed with a stud projecting through the opening in the side thereof, and a weight pivoted outside of said enlargement and adapted to bear on either side of said stud.
16. In combination with a railway car and its brakes, apparatus for manipulating the brakes comprising a fixed rack, a movable rack, a pinion adapted to roll on the fixed rack and raise the movable rack, a ratchet on the pinion, a lever pivoted on the pinion, a pawl pivoted to the lever to engage the ratchet, a detent to hold the movable rack in raised position, and a housing enclosing the pinion, ratchet and pawl having a surface against which the pawl is brought to bear on the back stroke of the lever to throw the pawl out of engagement with the ratchet.
17. In combination with a railway car and its brakes, apparatus for manipulating the brakes comprising a vertically movable member formed with two parallel series of teeth spaced apart and with a shoulder between them at the upper end of the member, means connecting said member with the brakes, a fixed support, a dog having a rocking bearing on said support adapted to engage said teeth and formed with a tail piece to extend between the teeth, and a weight pivoted to the support and adapted, in one position, to bear against the dog to hold the same against the movable member, and in another position to bear against the dog so as to tend to force it from engagement with the movable member, the shoulder on the upper end of the movable member being adapted to strike against the tail piece of the dog when the brakes are released so as to throw the weight from its inoperative to its operative position.
18. In combination with a railway car and its brakes, apparatus for manipulating the brakes comprising a housing, a vertically movable member in said housing formed with two parallel series of teeth spaced apart, a dog in said housing having a rock-

- ing bearing thereon formed with a tooth to engage the teeth of the vertically movable member and with a tail piece to project into the space between the teeth of the vertically 5 movable member, the housing having an opening in the side and the dog having a stud projecting therethrough, a weight pivoted to the outside of the housing adapted to be moved to bear against one side or the other of said stud to force the dog into or out of engagement with the vertically movable member, and a shoulder on the upper end of the vertically movable member adapted to strike against the tail piece of the dog, 10 when the brakes are released, to throw the weight from its inoperative to its operative 15 position.
19. In combination with a railway car and its brakes, apparatus for manipulating the 20 brakes comprising a housing on the car having a rack formed on the inside thereof, a rack bar movable in the housing, a pinion between the rack bar and rack, a hood on the housing open on one side, a ratchet 25 in the hood rigid with the pinion, a lever pivoted with respect to the ratchet, a pawl on the lever to engage the ratchet, said housing formed with an enlargement having an opening on one side, a dog having a rocking 30 bearing on said enlargement and formed with a stud projecting through the opening in the side thereof, and a weight pivoted outside of said enlargement and adapted to bear on either side of said stud, the housing 35 formed with a surface against which the pawl is adapted to bear, in raised position of the pinion and ratchet, and on the return stroke of the lever to effect disengagement of the pawl from the ratchet.
- 40 20. In combination with a railway car and its brakes, apparatus for manipulating the brakes comprising a housing on the car having a rack formed on the inside thereof, a rack bar movable in the housing having 45 two parallel series of holding teeth on one side thereof spaced apart and formed with a shoulder at its upper end between said series of teeth, a pinion between the rack bar and rack, a hood on the housing open at one side, 50 a ratchet in the hood rigid with the pinion, a lever pivoted with respect to the pinion, a pawl on the lever to engage the ratchet, said housing formed with an enlargement having an opening in one side, a dog having 55 a rocking bearing on said enlargement and formed with a stud projecting through the opening in the side thereof, and with a tail piece extending into the space between the two series of holding teeth, in the path 60 of said shoulder, and a weight pivoted outside of said enlargement and adapted to bear on either side of the stud on the dog.
21. In combination with a railway car and its brakes, apparatus for manipulating the 65 brakes comprising a housing formed with an interior rack, a rack bar, a pinion to travel on said rack and engage the rack bar, a lug on the rack bar projecting under the pinion, a brake connection secured to the lug, and means for raising and rotating 70 said pinion.
22. In apparatus for manipulating the brakes of a railway car, a fixed rack, a floating gear coacting with said rack, a movable member coacting with said gear to which 75 the brakes are connected, adapted to be given multiplied movement thereby, a housing adapted to enclose the moving parts, a step by step actuating means associated with the floating gear, means for holding the 80 movable member in the raised position, means to automatically release the holding means and return the movable parts to initial position instantaneously, and means to automatically reset the holding means simultaneously with the return of the parts to initial position.
23. In apparatus for manipulating the brakes of a railway car, the combination of a fixed gear rack, a movable spur gear operable upon said rack, a movable rack coacting with said movable gear to which the 90 brakes are connected, a bearing for said movable rack, means associated with said movable rack to hold the same in raised position, means associated with the holding means adapted to maintain the same in engagement and adapted to automatically release the holding means from engagement, and step by step means to actuate the spur 95 gear and the movable rack.
24. In apparatus for manipulating the brakes of a railway car, a frame provided internally with a fixed rack, a sliding rack to which the brakes are connected, a spur 100 gear coacting with the fixed rack and the sliding rack adapted to secure multiplied lifting, step by step actuating means associated with the movable spur gear, means associated with the sliding rack and means coacting therewith associated with the fixed 105 rack for providing a locking engagement of the sliding rack at varying elevations, an actuating means associated with the spur gear, automatic means to release the locking engagement for return of the sliding rack to initial position, and automatic means to reset the locking engagement means simultaneously with the return of the 110 sliding rack to initial position.
25. In apparatus for manipulating the brakes of a railway car, the combination of a spur gear mounted for rotation and bodily movement, a fixed rack and a movable rack engaged by said gear to which the 115 brakes are connected, an actuating mechanism transmitting movement step by step to the movable gear, means associated with the movable rack, and means, coacting therewith, associated with the fixed rack for hold- 120
- 125
- 130

ing the movable rack in raised position, means adapted to be set to release the holding means for return of the movable rack to initial position through operation of the actuating means.

26. In apparatus for manipulating the brakes of a railway car, the combination of a spur gear mounted for rotation and bodily movement, a fixed rack engaged by said gear, 10 a sliding rack coacting with said gear to which the brakes are connected, a power applying lever associated with said spur gear, a pawl and ratchet mechanism transmitting the movement of the lever to said gear, 15 means associated with said lever to automatically release the pawl from its ratchet engagement at any point of the movement of the spur gear along the line of the fixed rack, and locking means operably associated 20 with the movable rack and with the fixed rack.

27. In an apparatus for manipulating the brakes of a railway car, the combination of a fixed rack, a floating spur gear and a 25 movable rack meshing and coacting with the spur gear to which the brakes are connected, means for giving step by step rotary movements to the spur gear, a detent associated with the movable rack, retaining means engageable by the detent which is associated 30 with the fixed rack, means to automatically release the movable rack from locking engagement at any point of elevation to allow the same to fall, and means to automatically 35 reset the locking mechanism simultaneously with the return of the movable parts to initial position.

28. In an apparatus for manipulating the brakes of a railway car, the combination of 40 a housing, a fixed rack in said housing adapted to slide therein to which the brakes are connected, a bodily movable spur gear mounted to engage the fixed rack and the movable rack; power applying means associated with the spur gear, means for locking the movable rack at any point of its travel, means to instantaneously release the movable rack for return to initial position, and automatic means to reset the locking mechanism simultaneously with the return of the 45 movable rack to initial position.

29. In apparatus for manipulating the brakes of a railway car, the combination of a rectangular housing, a fixed rack upon 50 one of the internal sides of said housing, a spur gear engaging the said rack, a sliding rack engaging said gear to which the brakes are connected, a slot upon the face of said housing opposite the fixed rack adapted to 55 permit the travel of the sliding rack, means for propelling the spur gear, means upon said housing to limit the travel of the spur gear in either direction of its propulsion, means to automatically lock the sliding rack 60 at any position of its travel, means to re-

lease the locking means, a lug associated with the housing, and a pin associated with the locking mechanism adapted to cause an automatic return of the locking mechanism to locking position when the lifting mechanism is returned to its initial position.

30. In apparatus for manipulating the brakes of a railway car, the combination of a driven element to which the brakes are connected, a driving member provided with 75 releasable means for engaging the driven element, a detent for holding the driven element in the position to which it is moved, means adapted to be set to render said detent inoperative as soon as stress on the driven element is relieved by forward movement of the driving member, means actuated upon reverse movement of the driving member for disengaging the driving member from the driven element, and means whereby the detent is automatically reset to its holding position at the completion of the return movement of the driven element.

31. In apparatus for manipulating the brakes of a railway car, the combination of 90 a driven element to which the brakes are connected, provided with ratchet teeth, a driving member having a pawl for engaging said teeth, a detent for holding the driven element in the position to which it is moved, 95 means adapted to be set to render said detent inoperative as soon as stress on the driven element is relieved by a forward movement of the driving member, means actuated upon reverse movement of the driven member and 100 at any working position thereof for immediately disengaging the pawl from said ratchet teeth, and means whereby the detent is automatically re-set to its holding position at the completion of the return movement of the driven element.

32. In apparatus for manipulating the brakes of a railway car, the combination of 105 a movable rack to which the brakes are connected, a pinion to engage said rack and 110 impart movement thereto, an operating lever, a pawl and ratchet mechanism associated with the pinion and lever for giving step by step rotation to the pinion, a detent to hold the rack in the extended position, a trip member which may be set to render the detent inoperative as soon as the rack is relieved of stress by forward movement of the lever, and means whereby a reverse movement of the lever disengages the pawl from said ratchet.

33. In apparatus for manipulating the brakes of a railway car, the combination of 120 a movable rack to which the brakes are connected, a pinion to engage said rack and 125 impart movement thereto, an operating lever, a pawl and ratchet mechanism associated with the pinion and lever for giving step by step rotation to the pinion, a detent to hold the rack in the extended position, a trip member which may be set to render the 130

detent inoperative as soon as the rack is relieved of stress by forward movement of the lever, and means whereby a reverse movement of the lever, at any working position thereof, immediately disengages the pawl from the ratchet.

34. In apparatus for manipulating the brakes of a railway car, the combination of a movable rack to which the brakes are connected, a pinion to engage said rack and impart movement thereto, an operating lever, a pawl and ratchet mechanism associated with the pinion and lever for giving step by step rotation to the pinion, a detent to hold the rack in the extended position, a trip member which may be set to render the detent inoperative as soon as the rack is relieved of stress by forward movement of the lever, means whereby a reverse movement of the lever disengages the pawl from said ratchet, and means for automatically resetting the trip and detent to their holding positions when the rack, on release, reaches the end of its travel.

35. In apparatus for manipulating the brakes of a railway car, the combination of a stationary rack, a movable rack to which the brakes are connected, a pinion having interengagement with said racks and movable along the stationary rack, a ratchet wheel fixed to said pinion, an operating lever provided with a pawl to engage said ratchet wheel, a detent to hold the movable rack in the extended position, a trip member adapted to be set to render the detent inoperative as soon as the movable rack is relieved of stress by forward movement of the lever, and means whereby a reverse movement of the lever disengages the pawl from the ratchet.

36. In apparatus for manipulating the brakes of a railway car, the combination of a stationary rack, a movable rack to which the brakes are connected, a pinion having interengagement with said racks and movable along the stationary rack, a ratchet wheel fixed to said pinion, an operating lever having a pawl pivoted thereto to engage said ratchet, a detent to hold the movable rack in the extended position, a trip member which may be set to render the detent inoperative as soon as the rack is relieved of stress by forward movement of the lever, and means providing a surface extending parallel to the travel of said pinion with which said pawl is engaged, on reverse movement of the lever, to disconnect it from the ratchet.

37. In apparatus for manipulating the brakes of a railway car, the combination of a stationary rack, a movable rack to which the brakes are connected, a pinion having interengagement with said racks and movable along the stationary rack, a ratchet wheel fixed to said pinion, an operating lever having a pawl pivoted thereto to engage said

ratchet, a detent to hold the movable rack in the extended position, a trip member which may be set to render the detent inoperative as soon as the rack is relieved of stress by forward movement of the lever, means providing a surface extending parallel to the travel of said pinion with which said pawl is engaged, on reverse movement of the lever, to disconnect it from the ratchet, and means operative, when the movable rack on release reaches the end of its travel, to reset said detent and tripping member to their holding positions.

38. In apparatus for manipulating the brakes of a railway car, the combination of a housing having an internal, vertically disposed rack, a rack bar movable upwardly through said housing to which the brakes are connected, a pinion interposed between said rack and rack bar and adapted to travel along the rack, a ratchet wheel fixed to said pinion, an operating lever provided with a pivot pawl for engagement with said ratchet wheel, a detent pivoted to said rack bar, a series of holding teeth on the housing engageable by said detent, a tripping device pivoted to the rack bar and adapted to be set either to maintain the detent in engagement with the holding teeth to move the same away from the holding teeth, means on the housing providing a surface extending parallel to the travel of the pinion for disengaging the pawl from the ratchet on reverse movement of the lever, and a projection on the housing adapted to engage said tripping member and reset the same and said detent to their operative positions when the rack bar on release reaches the lower limit of its travel.

39. In combination with a railway car and its brakes, apparatus for manipulating the brakes comprising a member under the car which rocks in a plane substantially lengthwise of the car, a power applying device on the end of the car having an operating lever which oscillates in a plane substantially vertical and oblique to the plane of the rocking member, and connections between said rocking member and the brakes and power applying device, respectively.

40. In combination with a railway car and its brakes, apparatus for manipulating the brakes comprising a member under the car which rocks in a plane substantially lengthwise of the car, a power applying device on the end of the car having an operating lever which oscillates in a substantially vertical plane oblique to the end of the car, and connections between said rocking member and the brakes and power applying device, respectively.

41. In combination with a railway car and its brakes, apparatus for manipulating the brakes comprising a rocking member under the car, a power applying device on

the end of the car having an operating lever which oscillates in a substantially vertical plane oblique to the end of the car, and connections between said rocking member and the brakes and power applying device, respectively.

42. In combination with a railway car and its brakes, apparatus for manipulating the brakes comprising a member under the car having rolling movement in a plane substantially lengthwise of the car, a power applying device on the end of the car having an operating lever which oscillates in a substantially vertical plane oblique to the plane of the rolling member, and connections between said rolling member and the brakes and power applying device.

43. In combination with a railway car and its brakes, apparatus for manipulating the brakes comprising a member under the car which rocks in a plane substantially lengthwise of the car, a power applying device on the end of the car having a vertically movable element, and a lever which oscillates in a plane substantially vertical and oblique to the plane of the rocking member provided with means for giving step by step movement to the vertically movable element, and connections between the rocking member and the vertically movable element and the brakes, respectively.

44. In combination with a railway car and its brakes, of apparatus for manipulating the brakes comprising a member under the car which rocks in a plane substantially lengthwise of the car, a vertically movable rack on

the end of the car, a rod connecting the rocking member with said vertically movable element, a connection between said rocking member and the brakes, and a lever which oscillates in a plane at an angle to the plane of the rocking member provided with means for giving step by step movement upwardly to said vertically movable element.

45. The combination with a railway car and its brakes, of apparatus for manipulating the brakes comprising an operating lever arranged on a wall of the car to oscillate in a substantially vertical plane oblique to the plane of said wall, the car being provided with means for supporting the person operating the brakes between the lever and said wall.

46. In combination with a railway car and its brakes, apparatus for setting the brakes comprising a rack bar movable in the direction of its length, means for operatively connecting said rack bar to the brakes, driving means to impart movement to the rack bar comprising a pinion to engage the rack bar and a lever to rotate the pinion, a detent to hold the rack bar in its extended position, a trip member which may be set to render the detent inoperative as soon as the rack bar is relieved of stress by a forward movement of the lever, and means whereby a reverse movement of the lever frees the rack bar from the driving means to allow the same to return to the position from which it was moved.

AUGUSTUS F. KLASING.
